UNITED STATES PATENT OFFICE.

CHARLES A. ROBERTSON, OF JACKSON, MICHIGAN, ASSIGNOR TO MONTGOMERY WARD & COMPANY, OF CHICAGO, ILLINOIS, A CORPORATION OF ILLINOIS.

GOVERNOR FOR EXPLOSIVE ENGINES.

Application filed March 24, 1924. Serial No. 701,260.

The present invention is related to internal combustion engines, and has particular reference to the speed-governing devices thereof.

It has for its general object the improvement of such devices by the provision of mechanism which is extremely sensitive to fluctuations in the engine speed, so that the engine is rendered more responsive to such fluctuations and uniformity of its speed preserved.

A further object sought to be attained is the coordination and organization of the parts in such manner as to reduce the number thereof to a minimum, with a resultant decrease in liability to damage, and necessity for replacement because of undue wear.

The invention also has in view the incorporation in a speed governor of the class referred to of means which can be readily manipulated without the exercise of a high degree of skill, whereby to vary the effective adjustment of the elements through the medium of which the speed is governed.

Other objects and advantages will appear as the nature of the improvements is better understood, the invention consisting substantially in the novel construction, combination and arrangement of parts herein-after fully described, illustrated in the accompanying drawings, and finally pointed out in the appended claims.

The disclosure of the invention herein made is that of one practical embodiment thereof. Obviously, it is susceptible to change and variation in the form and arrangement of the structural elements, so that the disclosure is not to be taken as imposing restriction or limitation upon the invention beyond that which its position in the art may require.

In the drawings,

Fig. 1 is a top plan view of an explosive engine equipped with a speed governor constructed in accordance with the present invention;

Fig. 2 is a detail sectional plan view of the speed responsive devices and appurtenant parts;

Fig. 3 is a sectional elevation in detail on the line 3—3 of Fig. 1;

Fig. 4 is a similar view on the line 4—4, Fig. 1;

Fig. 5 is a similar view on the line 5—5, Fig. 4.

Referring now in detail to the accompanying drawings, and particularly to Fig. 1, in which the engine in its entirety is shown in plan view, the numeral 10 designates the frame of the engine, on which is mounted a cylinder 11, in which is disposed the usual piston having driving relation to a shaft 12 by the usual pitman or driving rod 13. The shaft 12 bears a pair of fly wheels 14, and also connected to said shaft 12 is a pinion 15 which meshes with a timing gear 16. The exhaust valve mechanism is designated by the numeral 17, a spark plug 18 being employed for igniting the explosive mixture, which plug is energized by a magneto 19 electrically connected with said spark plug 18 by a suitable conductor 20.

The invention is primarily concerned with the control of the ignition mechanism as the means for regulating the speed of the engine. To this end, the invention contemplates the provision of instrumentalities by which the operation of the magneto 19 is supervised so that when the engine has reached a maximum speed such operation may be so controlled as to prevent energizing of the spark plug 18, and thereby maintain the maximum speed or effect a reduction in the speed. For this purpose the speed-governing mechanism is associated with the means for operating the magneto 19, the latter being accomplished by the reciprocatory movement of a push rod 21 arranged at one side of the engine and acting on a rock lever 22, by means of which the exhaust valve mechanism 17 is actuated. The movement of the push rod 21 is transmitted to the trip mechanism 23 of the magneto 19 by a rocker arm 24 actuated in one direction by a spring 25 which encircles a contact sleeve 26, said sleeve and spring being interposed between the vertical member of the rocker arm 24 and a pair of locking nuts 27 adjustably mounted on the push rod 21. The spring 25 becomes compressed on movement of the rod 21 in the direction of the head of the engine cylinder, the contact sleeve 26 acting to initiate the throwing movement of the rocker arm 24 for releasing the trip mechanism 23, the spring 25 expanding to complete the throwing movement of the rocker arm 24 when the contact sleeve 26 has pushed said rocker arm to a predetermined point. The rocker arm 24 is re-set by a return spring 28 which swings the arm 24 in the opposite direction.

on the reverse movement of the push rod 21. The rocker arm 24 in its relation to the trip mechanism 23 of the magneto 19, together with the springs 25 and 28 in their association and cooperation with said rocker arm 24, the sleeve 26, and the push rod 21, constitute a timing mechanism for the magneto which is made the subject of another application filed concurrently herewith, Serial No. 701,261, such timing mechanism being fully described and claimed therein, and no claim thereto is incorporated herein. For operating the push rod 21 in one direction a timing cam 29 is employed. This cam is formed integral with the timing gear 16 at the inner face thereof, and about its hub portion, and its lobes are of such contour as to give the requisite reciprocation to the push rod 21, the latter being returned after reaching the limit of its movement in one direction by a return spring 30. The cam 29 has frictional engagement with a contact roller 31 journalled on a screw threaded stud 32 having a head 33 which fits in a countersunk recess at the outer side of the roller 31, thereby holding the latter in rotative relation to an elongated guide plate 34. One end of the plate 34 is turned inwardly to provide an attaching head 35, to which is connected the screw threaded end of the push rod 21, the latter being held in locked relation to the attaching head 35 by a fastening nut 36. The other end of the plate 34 is forked and provides a guide recess 37. The forked end of the plate 34 straddles a double flanged guide bushing 38, which is fitted to a neck 39 formed at the inner face of the cam 29 as an integral part thereof. Therefore, as the push rod 21 is reciprocated by the cam 29 in contact with the roller 31 and the return spring 28 acting in opposition to the cam 29, the forked end of the plate 34 moves within the flanges of the bushing 38, which, in turn, rotates with the cam 29 and the gear 16. This preserves the engaged relation of the plate 34 to the cam 29 for insuring proper operation of the latter on the roller 31.

The timing gear 16 rotates on an outwardly directed spindle 40 which is carried by a bearing stud 41 displaceably held in one side of the engine frame 10 by a set screw 42, held in adjusted position by a lock nut 43, the inner end of the screw 42 impinging against the inner end of the bearing stud 41. The spindle 40 is of less diameter than the stud 41, so that a bearing shoulder 44 is formed at the inner end of the spindle 40, and the bushing 38 bears against said shoulder, and thus is prevented moving beyond a predetermined point inwardly of the stud 41. At a point substantially midway the ends of the stud 41, and at its top portion, it is cut away to provide a diametrical slot, and in proximity to this cut away portion of the stud 41 the side of the engine frame 10 has

formed thereon an outwardly extending lug 45. To the lug 45 is pivotally connected, as by a bolt 46, or its equivalent, a swinging abutment plate 47. This includes a horizontal flange 48 and a vertical flange 49, the horizontal flange 48 being engaged, by an upwardly extending pin 50, carried by a governor rod 51 which is slidably mounted in the bore of the bearing stud 41. In the sliding movement of the rod 51, as will later appear, the pin 50 will move the abutment plate 47 towards and away from the engine frame 10, the plate swinging on its pivot 46, and thereby the free end of said plate is positioned for governing the movement of the push rod 21. For this purpose a contact button 51^a, which is preferably in the form of a square disk, is detachably seated in a countersunk recess 52 in the outer face of the vertical flange 49 of the contact plate 47, being held therein by a bolt 53 provided with a flared head which lies flush with the outer surface of the button 51^a. The latter has at opposite faces complementary countersunk recesses 54, so that the button is reversible and when the edges thereof become worn it may be shifted in its position to present not only a new edge of contact, but the faces thereof may be reversed in relation to the flange 49, thereby prolonging the life of the button. 95

At the inner face of the guide plate 34 a supporting slide 55 is provided. This slide has a forked end in which is fitted a contact button 56, similar in all respects to the button 51^a. The slide 55 is adjustable with respect to the plate 34 by means of a fastening bolt 57 which fits within an elongated slot 58, the end of the slide opposite to its forked end being turned inwardly to provide an engaging head 59 against which impinges the inner end of an adjusting screw 60. This screw is locked in its positions of adjustment by a nut 61. With the nut on the bolt 57 loosened, it is apparent that this bolt may be adjusted along the slot 58, carrying with it the supporting plate 55, the adjustment of which may be effected by the proper manipulation of the screw 60, and when the bolt 57 is clamped in adjusted position in its slot 58 the plate 55 will also be held in adjusted position. The contact button 56 is also held in adjusted position, both with respect to the supporting plate 55 and the guide plate 34, by a bolt 62, which fits within a slot 63 formed in said plate 34. The purpose of this is to permit proper adjustment of the button 56 so that its inner edge may contact with the outer edge of the button 51^a carried by the abutment plate 47, and it is the purpose of the adjustable mountings of the bolts 57 and 62 to insure this proper contact of the buttons 51^a and 56. It will be understood, of course, that with the button 51^a out of alignment with the button 56, such contact does not 130

take place, this relation of the parts being clearly shown in Fig. 2. When, however, the abutment plate 47 is swung away from the engine frame 10 by the governing mechanism about to be described, the alignment referred to will be effected, and on the movement of the push rod 21 towards the driving shaft 12, the button 56 will engage the button 51^a and arrest such further movement of the push rod. The effect of this will presently appear.

At the outer face of the timing gear 16 the same is provided with oppositely disposed pairs of spaced attaching ears 64. Between the ears of each pair is pivoted a weight 65, which constitutes an inertia element, a pin 66, or its equivalent, providing the pivot of each of these weights. The inner ends of the weights 65 are provided with inwardly directed cam projections 67, and said projections are designed to bear against a thrust washer 68 which is mounted on the governor rod 51. The inner face of this thrust washer is grooved transversely, as at 69, and thus provides a guideway in which the cam projections 67 are seated, and this engagement causes the thrust washer 68 to rotate about the governor rod 51 as the timing gear 16 is rotated. The washer 68 bears against a spacing washer 69^a which is held in position on the rod 51 by a nut 70.

Each of the cam projections 67, at its inner edge, is also provided with a contact head 71 designed to engage the outer face of the timing gear 16, and thereby limit the inward movement of the cam projections 67, and still preserve the parallel relation of the faces of the weights 65 with the face of the gear 16.

During the rotation of the gear 16, when the same has attained a speed sufficiently great, centrifugal force will cause the weights 65 to swing on their pivots, and move the cam projections 67 outwardly, or away from the face of the timing gear 16. In this movement of the projections pressure is exerted against the thrust washer 68 and the governor rod 51 is thereby pulled outwardly, or in a direction away from the engine frame 10. Such movement swings the abutment plate 47 on its pivot 46, thereby aligning the contact button 51^a with the contact button 56, if the force exerted by the weights 65 is sufficient to swing the abutment plate 47 to that extent. When the governor rod 51 is so moved a coil spring 72 is compressed. This spring encircles the inner end of the rod 51, the inner end of said spring abutting against a head 73 riveted, or otherwise secured to said rod. A bushing 74 also encircles the inner end of the rod 51 and encases the spring 72, the inner end of the latter abutting against the inner end of the bushing 74. The bushing

74 is fitted within a socket 75 formed at the inner end of the bearing stud 41, said bushing 74 having a flange 76 of greater diameter than the bore of the socket 75. Thus it will be seen that the bushing 74 is restrained against inward movement, and as the rod 51 is drawn inwardly under the influence of the weights 65, the head 73 compresses the spring 72, and this spring, therefore, resists the inward movement of the rod 51. In thus becoming compressed the spring 72 will react to draw the rod 51 inwardly, or towards the engine frame 10, when the speed of the wheel 16 has become reduced, and the inertia of the weights 65 overcome, and in such retraction of the rod 51 the abutment plate 47 will be drawn towards the engine frame, thus swinging the contact button 51^a out of alignment with the contact button 56, whereupon the guide plate 34, impelled by the push rod 21, may move to the full limit of its travel in the direction towards the driving shaft 12.

For manually controlling the setting of the herein described governor mechanism to vary the limits of the speed there is associated with the governor rod 51 and the flanged bushing 74 an adjusting slide 77. This is in the form of a forked plate at the inner edge of each leg of which is provided a wedge-shaped flange 78 tapering from its upper end to the lower end thereof. The legs of said plate 77 are disposed between the flange 76 of the bushing 74 and the inner end of the bearing stud 41, as clearly illustrated in Figs. 2, 4 and 5. Fixedly connected to the upper end of the plate 77 is a handle member 79 terminating in its upper end in a finger loop 80. The handle member 79 passes through a slotted latch plate 81, which is connected to the engine frame preferably by the set screw 42 and its locking nut 43, by which the bearing stud 41 is held in position. The handle member 79 is provided with a series of transverse corrugations 82 by which a series of spaced ribs is formed in said handle member, and said ribs are designed to engage the edges of the slot in the latch plate 81, through which the handle member 79 is passed. This engagement holds the plate 77 at different elevations and thus determines the degree of compression of the spring 72 effected by forcing the flange 76 of the bushing 74 outwardly. Obviously, when the slide plate 77 is in its uppermost position no outward pressure is exerted on the bushing 74, and the spring 72 has the least degree of compression thereon. This is the low speed limit of the engine.

When the slide 77 is pushed downwardly to its lowermost position the flanges 78, acting as cams, force the bushing 74 outwardly, thereby placing the greatest degree of compression on the spring 72. As the spring 72 thus is highly compressed, greater effort of

the weights 65, in their outward movement, is necessary to overcome such compression, and in this lowermost position of the slide 77 the high speed limit of the engine is reached. If the handle member 79 be operated to move the plate 77 at any intermediate positions between the high and low limit of speed defined by the extreme travel of the plate 77, the speed of the engine is varied within these limits, and in accordance with the positioning of the slide 77.

In the light of the foregoing explanation the operation of the speed governing mechanism herein described will be readily understood, and briefly described is as follows:

Assuming the speed changing slide 79 to be at its uppermost position, and the engine to be operating, the inertia elements 65 are in their normal or retracted positions, and the abutment plate 47 is in such relation to the engine frame 10 that the contact button 51^a is out of alignment with the contact button 56. As the timing gear 16 rotates, the cam 29, acting through the roller 31, pushes the rod 21 in the direction of the head of the engine cylinder. The magneto 19 is actuated so as to produce a spark at the terminals of the spark plug 18, and the explosive force of the combustible mixture thus imparts an impulse to the piston. If the speed of the engine increases, the weights 65 swing on their pivots, thereby pulling the governor rod 51 outwardly and eventually swinging the abutment plate 47 also sufficiently outwardly to align the contact button 51^a with the contact button 56. When this arises, movement of the push rod 21 under influence of the return spring 30 is arrested, and the push rod 21 thereafter is precluded actuating the magneto. No spark takes place, and this condition continues until the speed of the engine is reduced, whereupon the weights 65 approach their normal position, and in doing so the spring 72 expands to retract the governor rod 51. This draws the abutment plate 47 inwardly towards the frame 10 and disaligns the contact buttons 51^a and 56. The push rod 21 may now move to the extreme limit of its travel towards the engine shaft 12, thus permitting the magneto 19 again to be actuated when the rod 21 is moved in the opposite direction by the cam 29, and energizing the spark plug 18 to enable the engine to resume the speed for which it is set.

To vary the speed of the engine the speed changing slide 77 is positioned with respect to the flanged bushing 74 in the manner previously described, and at varying points between the extremes of movement of that slide, thereby imparting varying degrees of compression on the spring 72, and thus requiring different degrees of pressure of the weights 65 on the rod 51 to swing the abutment plate 47.

The handle member 79 of the speed changing slide 77 passes upwardly through a slot 83 in a cover 84 which extends over the crank case of the engine frame 10. This positions the finger loop 80 in convenient location for ready access by the operator for adjustment.

I claim:

1. In a governor of the class described, the combination with the ignition mechanism of an explosive engine, and the actuating means thereof for effecting the generation of a spark thereby, of an abutment hingedly mounted with respect to the engine frame and adapted to be swung into the path of movement of said actuating means, whereby to arrest movement of the latter and to prevent generation of the spark, a member slidably mounted and controlled by the speed of the engine for swinging said abutment into engagement with said actuating means when a predetermined speed has been attained, and means for releasing the abutment from engagement with the actuating means when the speed has been reduced.

2. In a governor of the class described, the combination with the ignition mechanism of an explosive engine, and the actuating means thereof for effecting the generation of a spark thereby, of an abutment hingedly mounted with respect to the engine frame and adapted to be swung into the path of movement of said actuating means, whereby to arrest movement of the latter and to prevent generation of the spark, a member slidably mounted and controlled by the speed of the engine for swinging said abutment into engagement with said actuating means when a predetermined speed has been attained, means for restraining movement of said slidably mounted member, and means for actuating the slidably mounted member controlled by the speed of the engine for swinging said abutment into engagement with the actuating means when said predetermined speed has been attained.

3. In a governor of the class described, the combination with the ignition mechanism of an explosive engine, and the actuating means thereof for effecting the generation of a spark thereby, of an abutment hingedly mounted with respect to the engine frame and adapted to be swung into the path of movement of said actuating means, whereby to arrest movement of the latter and prevent generation of the spark, a member slidably mounted and controlled by the speed of the engine for swinging said abutment into engagement with said actuating means when a predetermined speed has been attained, means for actuating the slidably mounted member controlled by the speed of the engine for swinging said abutment into engagement with the actuating means when said predetermined speed has been attained.

and resilient means for restraining movement of said slideable member and for releasing the abutment from engagement with the actuating means when the speed has been reduced.

4. In a governor of the class described, the combination with the ignition mechanism of an explosive engine, and the actuating means thereof for effecting the generation of a spark thereby, of a swinging abutment associated with said actuating means and cooperating therewith to arrest movement of the actuating means, whereby to prevent generation of the spark, means controlled by the speed of the engine for engaging said abutment with said actuating means when a predetermined speed has been attained, and means associated with said controlling means for varying the degree of its response to the speed of the engine, whereby to vary the speed of the engine.

5. In a governor of the class described, the combination with the ignition mechanism of an explosive engine, and the actuating means thereof for effecting the generation of a spark thereby, of a swinging abutment associated with said actuating means and cooperating therewith to arrest movement of the actuating means, whereby to prevent generation of the spark, means controlled by the speed of the engine for engaging said abutment with said actuating means when a predetermined speed has been attained, means associated with said controlling means for varying the degree of its response to the speed of the engine, whereby to vary the speed of the engine, and means for releasing the abutment from engagement with the actuating means when the speed has been reduced.

6. In a governor of the class described, the combination with the ignition mechanism of an explosive engine, and the actuating means thereof for effecting the generation of a spark thereby, of means cooperating with the actuating means to arrest movement thereof, whereby to prevent generation of the spark, means controlled by the speed of the engine for engaging said arresting means with said actuating means when a predetermined speed has been attained, and means associated with said controlling means for varying the degree of its response to the speed of the engine, whereby to vary the speed of the engine.

7. In a governor of the class described, the combination with the ignition mechanism of an explosive engine, and the actuating means thereof for effecting the generation of a spark thereby, of means cooperating with the actuating means to arrest movement thereof, whereby to prevent generation of the spark, means controlled by the speed of the engine for engaging said arresting means with said actuating means when a predetermined speed has been attained, and means associated with said controlling means for varying the degree of its response to the speed of the engine, whereby to vary the speed of the engine, and means for releasing said arresting means from engagement with the actuating means when the speed has been reduced.

mined speed has been attained, means associated with said controlling means for varying the degree of its response to the speed of the engine, whereby to vary the speed of the engine, and means for releasing said arresting means from engagement with the actuating means when the speed has been reduced. 70

8. In a governor of the class described, the combination with the ignition mechanism of an explosive engine, and the actuating means thereof for effecting the generation of a spark thereby, of means cooperating with the actuating means to arrest movement thereof, whereby to prevent generation of the spark, means controlled by the speed of the engine for engaging said arresting means with said actuating means when a predetermined speed has been attained, and a manually operated device cooperating with said controlling means for varying the degree of its response to the speed of the engine, whereby to vary the speed of the engine. 75 80 85

9. In a governor of the class described, the combination with the ignition mechanism of an explosive engine, and the actuating means thereof for effecting the generation of a spark thereby, of means cooperating with the actuating means to arrest movement thereof, whereby to prevent generation of the spark, means controlled by the speed of the engine for engaging said arresting means with said actuating means when a predetermined speed has been attained, a manually operated device cooperating with said controlling means for varying the degree of its response to the speed of the engine, whereby to vary the speed of the engine, and means for locking said manually operated device 105 in its positions of adjustment. 90 95

10. In a governor of the class described, the combination with the ignition mechanism of an explosive engine and the actuating means thereof for effecting the generation of a spark thereby, of means cooperating with the actuating means to arrest movement thereof, whereby to prevent generation of the spark, means controlled by the speed of the engine for engaging said arresting means with said actuating means when a predetermined speed has been attained, a manually operated device cooperating with said controlling means for varying the degree of its response to the speed of the engine, whereby to vary the speed of the engine, and means for releasing said arresting means from engagement with the actuating means when the speed has been reduced. 110 115 120

11. In a governor of the class described, the combination with the ignition mechanism of an explosive engine, and the actuating means thereof for effecting the generation of a spark thereby, of means cooperating with the actuating means to arrest move- 125 130

- ment thereof, whereby to prevent generation of the spark, means controlled by the speed of the engine for engaging said arresting means with said actuating means 65
6 when a predetermined speed has been attained, a manually operated device cooperating with said controlling means for varying the degree of its response to the speed of the engine, whereby to vary the speed of the engine, means for locking said manually operated device in its positions of adjustment, and means for releasing said arresting means from engagement with the actuating means when the speed has been reduced.
- 10 12. In a governor of the class described, the combination with the ignition mechanism of an explosive engine, and the actuating means thereof for effecting the generation of a spark thereby, of a swinging abutment associated with said actuating means and cooperating therewith to arrest movement of the actuating means, whereby to prevent generation of the spark, means controlled by the speed of the engine for engaging said abutment with said actuating means when a predetermined speed has been attained, a manually controlled device cooperating with said controlling means for varying the degree of its response to the speed of the engine whereby to vary the speed of the engine, and means for locking said manually operated device in its positions of adjustment. 15
- 15 13. In a governor of the class described, the combination with the ignition mechanism of an explosive engine, and the actuating means thereof for effecting the generation of a spark thereby, of a swinging abutment associated with said actuating means and cooperating therewith to arrest movement of the actuating means, whereby to prevent generation of the spark, a slid- 20 able member controlled by the speed of the engine for swinging said abutment into engagement with said actuating means when a predetermined speed has been attained, a manually operated device cooperating with said slid- able member and adapted to position the latter at different points of responsiveness to the speed of the engine, whereby to vary the speed of the engine, and means for releasing said arresting means from engagement with the actuating means when the speed has been reduced.
- 25 14. In a governor of the class described, the combination with the ignition mechanism of an explosive engine, and the actuating means thereof for effecting the generation of a spark thereby, of a swinging abutment associated with said actuating means and cooperating therewith to arrest movement of the actuating means, whereby to prevent generation of the spark, a slid- 25 able member controlled by the speed of the engine for swinging said abutment into engagement with said actuating means when a predetermined speed has been attained, a manually operated device cooperating with said slid- able member and adapted to position the latter at different points of responsiveness to the speed of the engine, whereby to vary the speed of the engine, and means for releasing said arresting means from engagement with the actuating means when the speed has been reduced.
- 30 15. In a governor of the class described, the combination with the ignition mechanism of an explosive engine, and the actuating means thereof for effecting the generation of a spark thereby, of a swinging abutment mounted at the side of the engine frame and hingedly connected thereto, said swinging abutment co-operating with said actuating means to arrest movement of the same when brought into engagement therewith, whereby to prevent generation of the spark, a hollow stud carried by the engine frame, a gear rotatably mounted thereon, a slid- 35 able member mounted in the bore of said stud and connected to said swinging abutment, means for actuating said slid- able member to swing the abutment into engagement with said actuating means when a predetermined speed has been attained, and means for releasing the abutment from engagement with the actuating means when the speed of the engine has been reduced.
- 40 16. In a governor of the class described, the combination with the ignition mechanism of an explosive engine, and the actuating means thereof for effecting the generation of a spark thereby, of a swinging abutment mounted at the side of the engine frame and having one of its ends hingedly connected thereto, the other end of said swinging abutment co-operating with said actuating means to arrest movement of the same when brought into engagement therewith, whereby to prevent generation of the spark, a hollow stud carried by the engine frame, a rotat- 45 ing element mounted on said stud and actuated by the engine shaft, a slid- able member mounted in the bore of said stud and connected to said swinging abutment, means carried by said rotating element for actuating said slid- able member to swing the abutment into engagement with said actuating means when a predetermined speed has been attained, and means for releasing the abutment from engagement with the actuating means when the speed of the engine has been reduced.
- 50 17. In a governor of the class described, the combination with the ignition mechanism of an explosive engine, and the actuating means thereof for effecting the genera- 55
- 65 70 75 80 85 90 95 100 105 110 115 120 125

tion of a spark thereby, of a swinging abutment mounted at the side of the engine frame and having one of its ends hingedly connected thereto, the other end of said swinging abutment co-operating with said actuating means to arrest movement of the latter when brought into engagement therewith, whereby to prevent generation of the spark, a hollow stud carried by the engine frame, a rotating element mounted on said stud and actuated by the engine shaft, a slidable member mounted in the bore of said stud and connected to said swinging abutment, centrifugally-operating means carried by said rotating element for actuating said slidable member to swing the abutment into engagement with said actuating means when a predetermined speed has been attained, and means for releasing the abutment from engagement with the actuating means when the speed of the engine has been reduced.

18. In a governor of the class described, the combination with the ignition mechanism of an explosive engine, and the actuating means thereof for effecting the generation of a spark thereby, of a swinging abutment mounted at the side of the engine frame and having one of its ends hingedly connected thereto, the other end of said swinging abutment co-operating with said actuating means to arrest movement thereof when brought into engagement therewith, whereby to prevent generation of the spark, a hollow stud carried by the engine frame, a rotating element mounted on said stud and actuated by the engine shaft, a slidable member mounted in the bore of said stud and connected to said swinging abutment, means carried by said rotating element and connected to said slidable member for actuating the latter to swing the abutment into engagement with said actuating means when a predetermined speed has been attained, and means also connected to said slidable member and acting in opposition to the last mentioned means for releasing the abutment from engagement with the actuating means when the speed of the engine has been reduced.

19. In a governor of the class described, the combination with the ignition mechanism of an explosive engine, and the actuating means thereof for effecting the generation of a spark thereby, of a swinging abutment mounted at the side of the engine frame and having one of its ends hingedly connected thereto, the other end of said swinging abutment co-operating with said actuating means to arrest movement thereof when brought into engagement therewith, whereby to prevent generation of the spark, a hollow stud carried by the engine frame, a rotating element mounted on said stud and actuated by the engine shaft, a slidable member mounted in the bore of said

stud and connected to said swinging abutment, means carried by said rotating element for actuating said slidable member to swing the abutment into engagement with said actuating means when a predetermined speed has been attained, means for releasing the abutment from engagement with the actuating means when the speed of the engine has been reduced, and means co-operating with said slidable member to position the latter at different points of responsiveness to the speed of the engine, whereby to vary the speed of the engine.

20. In a governor of the class described, the combination with the ignition mechanism of an explosive engine, a push rod for actuating the same for effecting the generation of a spark thereby, a guide plate carried by said push rod, and a contact carried by said guide plate, of a swinging abutment mounted at the side of the engine frame and having one of its ends hingedly connected thereto, the other end of said swinging abutment co-operating with said contact to arrest movement of the push rod when the abutment is brought into engagement with the contact, whereby to prevent generation of the spark, a hollow stud carried by the engine frame, a rotating element mounted on said stud and actuated by the engine shaft, a slidable member mounted in the bore of said stud and connected to said swinging abutment, means carried by said rotating element for actuating said slidable member to swing the abutment into engagement with said contact when a predetermined speed has been obtained, means for releasing the abutment from engagement with the contact when the speed of the engine has been reduced, and means co-operating with said slidable member to position the latter at different points of responsiveness to the speed of the engine, whereby to vary the speed of the engine.

21. In a governor of the class described, the combination with the ignition mechanism of an explosive engine, a push rod for actuating the same for effecting the generation of a spark thereby, a guide plate carried by said push rod, and a contact carried by said guide plate, of a swinging abutment mounted at the side of the engine frame and having one of its ends hingedly connected thereto, the other end of said swinging abutment co-operating with said contact to arrest movement of the push rod when the abutment is brought into engagement with the contact, whereby to prevent generation of the spark, a hollow stud carried by the engine frame, a gear mounted on said stud and rotatable with respect thereto, said gear being actuated by the engine shaft, a governor rod slidably mounted in the bore of said stud and connected to said swinging abutment, means carried by said gear for

actuating said governor rod to swing the abutment into engagement with said contact when a predetermined speed has been obtained, means for releasing the abutment from engagement with the contact when the speed of the engine has been reduced, and means co-operating with said governor rod

to position the latter at different points of responsiveness to the speed of the engine, whereby to vary the speed of the engine. ¹⁰

In testimony whereof I have hereunto signed my name.

CHARLES A. ROBERTSON.
